BOTTLE

Bruce L. Roberts, Rossford, Ohio, assignor to Owens-Illinois, Inc., Toledo, Ohio, a corporation of Ohio
Filed Oct. 23, 1965, Ser. No. 87,843

Term of patent 14 years

(Cl. D58—8)

FIG. 1

FIG. 1 is a front elevational view of a bottle showing my new design.

FIG. 2 is a top plan view thereof.

FIG. 3 is an enlarged fragmentary sectional view taken through line 3—3 of FIG. 1.

The side opposite that seen in FIG. 1 is the same as the side shown.

The characteristic features of this design reside in the configuration shown in full lines on the drawing.

I claim:

The ornamental design for a bottle, substantially as shown and described.
